UNITED STATES PATENT OFFICE

98,551

DESIGN FOR A COMBINED TOILET CABINET AND BUREAU OR THE LIKE

Irving H. Stern, Boston, Mass.

Application February 21, 1935, Serial No. 55,547

Term of patent 7 years

To all whom it may concern:

Be it known that I, Irving H. Stern, a citizen of the United States, residing at Boston, in the county of Suffolk and State of Massachusetts, have invented a new, original, and ornamental Design for a Combined Toilet Cabinet and Bureau or the like, of which the following is a specification, reference being had to the accompanying drawing, forming a part thereof.

The single figure of the drawing shows a per-

spective view of a combined toilet cabinet and bureau or the like illustrating my new design.

The dominant features of the design are shown in full lines.

I claim:

The ornamental design for a combined toilet cabinet and bureau or the like, as shown and described.

IRVING H. STERN.
